UNITED STATES PATENT OFFICE

THOMAS O'CONNOR, OF DAYTON, OHIO, ASSIGNOR TO OHMER FARE REGISTER COMPANY, OF DAYTON, OHIO

REGISTER INTERLOCKING MECHANISM

Application filed June 17, 1929. Serial No. 371,482.

This invention relates to an improved interlocking mechanism for registers and by way of illustration is shown as applied to that type of register disclosed in the application of 5 Albert S. Wheelbarger and Grover C. Coil, Serial No. 65,532, filed October 29, 1925.

More specifically, the invention relates to a locking means to prevent the operation of the printing shaft when any one of the keys of 10 the register is in improper position or when the operator's key is removed from the machine.

Referring to the drawing in which I have shown an embodiment of my invention by 15 way of illustration

Fig. 1 is a side elevational view thereof.

Fig. 2 is a perspective view of the printing knob and a portion of the associated mechanism.

20 Fig. 3 is a side elevational view of the operator's key.

Fig. 4 is a perspective view of the operating knob for the printing shaft and the connections between the said knob and the 25 said shaft.

In Fig. 1 I have shown the lever 1 which is operated by the clerk to set up amounts of money, classes of transactions and other indicia as may be desired. This lever is the setting key and corresponds to the push buttons 30 as commonly used on cash registers. While I have shown only one such lever it will be understood, of course, that any number of levers may be employed to designate cents, dimes, dollars, et cetera. The lever 1 is formed integral with a segmental gear 2, both of which are loosely mounted on a shaft 3. The segmental gear 2 is provided with teeth 4 which cooperate with a roller 5 mounted on a pin 6 carried by an arm 7 which is loosely 40 mounted on a shaft 8 carried by the framework of the machine. The arm 7 is provided with an arm 9 extending above the shaft 8 and is connected by means of a spring 10 with the shaft 11 carried by an extension 12 of the machine frame 13. The spring 10 always urges the roller 5 into engagement with the segmental gear 2 and said roller normally lies in between adjacent teeth. As the lever 1 is pulled forward or pushed rearwardly the

roller 5 rides over as many teeth as the lever 1 advances or retards the segmental gear and thus the arm 7 during such movement oscillates back and forth. When, however, the lever 1 is in correct position so as to indicate a digit the roller 5 will lie in between two of the teeth 4 and will therefore tend to hold resiliently the lever 1 in its adjusted position. It will of course be understood that there are as many rollers 5, arms 7, et cetera, as there are segmental gears 2 or lever 1.

Surrounding the shaft 8 is a sleeve 14 which has a downwardly projecting arm 15 which carries a shaft 16 which lies immediately behind the arm 7 and in engagement therewith. The said sleeve 14 is also provided with an arm 17 which carries a pin 18 connected to a spring 19 secured by a pin 20 to the frame 13. This spring 19 pulls upwardly on the arm 17 and holds the shaft 16 in engagement with the arm 7. The sleeve 14 is also provided with an arm 21 which carries a pin 22 which extends outwardly through a slot 23 in the frame 13.

A two-armed lever 24 is pivoted on a stud 25 and is normally pulled upwardly by means of a spring 26. One of the arms 27 of the said lever 24 is provided with an enlargement having a substantially vertical face 28 which engages the pin 22. The other arm 29 of the lever 24 is bifurcated and between the bifurcations thereof receives the operator's key 30. This key is provided with a cam 31 on the lower edge thereof so that when the key is inserted it will engage the lower branch of the arm 29 and will press the same downwardly rotating the arm 27 slightly in a clockwise direction as viewed in Fig. 1 so as to disengage the face 28 from the pin 22.

An arm 32 is pivoted on the arm 27 by means of a stud 33 which arm is provided with an extension which has a face 34 adapted to engage the pin 22. This arm 32 is urged in a clockwise direction by means of a spring 35 and at its lower end it is bifurcated 36 and receives a pin 36 carried by a lever 37 pivoted on a pin 38 which lever 37 is provided with a laterally extending portion 39 which terminates in an arm 40 as clearly shown in Fig. 2.

If any one of the levers 1 is in incorrect position, the roller 5 will be on top of a tooth 4 which will hold the arm 7 outwardly and the pin 22 will thereby hold the arm 40 in lowered position since the pin 22 will have rotated the arm 32 in a counter-clockwise direction which action will have slightly rotated the lever 37 in a clockwise direction. In like manner the arm 40 will be in its lowered position if the operator's key 30 is removed for when it is removed the spring 26 will pull the lever 24 upwardly so that the face 28 will engage the pin 22 and move it against the face 34 of the lever 32 rotating said lever 32 counter-clockwise which slight motion will rotate to a corresponding extent the lever 37 clockwise and lower the arm 40. The arm 40 therefore is normally in the position shown in Fig. 1 when the operator's key 30 is in the machine and each of the levers 1 is in correct position but if any lever 1 is in incorrect position or if the operator's key 30 is removed the arm 40 will be lowered from the position in which it is shown in Fig. 1.

25 A knob 41 is secured to a sleeve 43 rotatably mounted on a shaft 42 which sleeve 43 carries a lug 44 which normally lies in a plane nearer to the casing 13 than is the arm 40. When the arm 40 is in its lowered position it prevents the operator pulling outwardly on the knob 41. The sleeve 43 is cut away longitudinally forming a groove 45 adapted to receive a tongue 46 on a shaft 47. The shaft 47 is the operating shaft for the totalizer printing mechanism not shown. A plate 48 is secured to the frame 13 which plate carries a square lug 49 which normally extends into the groove 45 and locks the knob 41 against rotation.

30 When it is desired to operate printing operating shaft 47 it is necessary to pull outwardly on the knob 41 so as to disengage the groove 45 from the lug 49. This is impossible if any one of the levers 1 is in improper position or if the operator's key 30 is not in the machine since under any of these conditions the arm 40 would over-lie the lug 44. If, however, all of the levers 1 are in proper position and if the operator's key 30 is inserted in the machine the spring 35 will elevate the arm 40 above the lug 44 so that the operator can disengage the groove 45 from the lug 49 by pulling outwardly on the knob 41. The operator can now rotate the knob 41 in a clockwise direction as viewed in Fig. 1 thereby rotating the printing operating shaft 47 through the tongue 46 and groove 45. He is prevented from rotating the knob 41 in an anti-clockwise direction by means of an arm 50 pivoted on the shaft 38 normally pulled downwardly by means of a spring 51.

Having now described my invention by way of illustration I claim:

1. In a machine, a setting lever, a second lever, means whereby said second lever is held

in one position when said setting lever is in proper position and is held in another position when said setting lever is in improper position, a shaft, a knob having splined connection with said shaft, means to prevent the rotation of said knob and said shaft until said knob is moved longitudinally of said shaft and means controlled by said second mentioned lever to prevent said knob from being moved longitudinally of said shaft when said setting lever is in improper position. 70 75

2. In a machine, an operator's key, a lever moved by said key when said key is being inserted in the machine, a setting key, a second lever, means whereby said second lever is held in one position when said setting key is in proper position and in another position when said setting key is in improper position, a third lever, means whereby said third lever is held in a position corresponding to the position in which said second-mentioned lever is held, a pin controlled by both said first-mentioned and third-mentioned levers, a shaft, a knob having a splined relation to said shaft, means whereby said knob is held against rotation until it is moved longitudinally of said shaft and means whereby said knob is held against being moved longitudinally of said shaft unless said pin is in a given position. 80 85 90 95

3. In a machine, an operator's key, a lever, means whereby said lever is moved when said key is being inserted in the machine, a second lever pivoted to said first-mentioned lever, a setting lever, means whereby the position of said second-mentioned lever is controlled by either said setting lever or said first-mentioned lever, a shaft, a knob having a splined relation to said shaft, means to prevent the rotation of said shaft and knob unless said knob has been moved longitudinally of said shaft, and means controlled by said second-mentioned lever to prevent said knob from being moved longitudinally of said shaft unless said operator's key is properly inserted 100 105 110 and said setting key is in proper position.

In testimony whereof I affix my signature.

THOMAS O'CONNOR.
